UNITED STATES PATENT OFFICE.

FRANCIS ALEXANDER STIERHEIM, OF PITTSBURGH, PENNSYLVANIA.

HACK-SAW FRAME.

Application filed January 23, 1924. Serial No. 687,993.

To all whom it may concern:

Be it known that I, FRANCIS ALEXANDER STIERHEIM, a citizen of the United States, and a resident of Pittsburgh, in the county 5 of Allegheny and State of Pennsylvania, have invented certain new and useful Improvements in Hack-Saw Frames, of which the following is a specification.

This invention relates to an improvement 10 in hack saw frames, and has for its object to provide a simple and compact structure of this character which is extensible and adjustable so as to be equally well adapted to be advantageously used upon work of large 15 or small dimensions.

A further object is to provide a hack saw frame having the foregoing enumerated advantages and capacities and wherein the parts of the frame are releasably locked in 20 assembly so as to give to the frame the desirable rigidity.

A still further object is to provide a hack saw frame of the character specified and wherein provision is made for the utilization 25 of broken blades.

Other objects and advantages of the invention reside in certain novel features of the construction, combination and arrangement of parts which will be hereinafter more 30 fully described and particularly pointed out in the appended claims, reference being had to the accompanying drawings forming part of this specification, and in which:

Figure 1 is a fragmentary view in side elevation, showing one embodiment of the invention;

Figure 2 is a top plan view of the device shown in Figure 1;

Figure 3 is a view thereof, partly in vertical section and partly in elevation;

Figures 4 and 5 are views in section on lines 4—4 and 5—5 respectively of Figure 1;

Figure 6 is a fragmentary view in side elevation of another form of the invention;

Figure 7 is a fragmentary perspective view, showing the handle employed in Figure 6; and

Figure 8 is a view in section on line 8—8 of Figure 6.

Referring to the drawings and more especially to Figures 1 to 5 inclusive, the numeral 1 designates the body portion or bridge bar of the hacksaw frame which comprises an elongated solid bar of metal of rectangular cross section and having smooth exterior faces.

At one end of the body portion 1, a fixed leg 2 is arranged, the leg 2 being fixed with respect to the longitudinal axis of the body portion but being extensible as will presently appear. The leg 2 consists of a fixed member 3 of tubular form and having curved attaching wings 4 fixed to an end of the body portion 1. An adjustable member 5 is slidably fitted in the tubular member 3 and is releasably secured in adjusted position with respect to the tubular member. At one end of the adjustable member 5 an adjustable saw holder 6 of conventional construction is releasably secured.

A slide 7 is fitted for longitudinal adjustment on the end of the body portion 1 opposite the fixed leg and constitutes an element of the movable leg of the frame which is designated generally at 8. This movable leg includes the slide 7, a solid bar 9 pivoted to the slide, as at 7a and constituting the fixed member of the leg, and a tubular member 10 slidably fitted on the bar 9. The tubular member 10 is made of resilient metal and has a slot 11 and a pair of clamping ears 12 having threaded apertures and cooperable with a clamping screw or bolt and nut 13 whereby the hollow member may be releasably secured in adjusted position on the fixed member 9. The inner end of the bar 9 is beveled to provide a bit or knife edge 9a adapted to have biting engagement with the body portion 1 to hold the slide in longitudinal adjustment thereon. The outer end 90 of the tubular member 10 is formed and adapted to have mounted thereon an adjustable saw holder 14 cooperable with the holder 6 to hold the saw blade on the frame. The holder 14 may be of conventional construction or it may have an integral tubular portion 15 designed to receive an end of a broken saw blade. In the tubular portion a transverse slot 16 is provided and intersects the opening of the tubular portion so that a 100 wedge 17 inserted in the slot 16 will have its sharp edge disposed to engage the teeth of the broken saw blade.

In practice, with this form of the invention, when the saw blade is assembled and 105 tightened up in the holders 6 and 14, the knife edge 9a is forced into biting engagement with the body portion 1 and the parts are locked in position and the desired rigidity of the frame is had. Prior to tightening up the saw in the holders 6 and 14, the desired longitudinal adjustment of the slide 110

7 along the body portion 1 may be effected. The legs 2 and 8 are readily extensible to adapt the frame for use on large as well as small work and in all adjustments a compact and effective frame is provided.

5 A handle 19 may be conveniently secured to the slide 7 to afford a means for manipulating the saw.

10 It is to be noted that as shown in the drawings the legs of the saw frame diverge slightly from each other and as a consequence of this arrangement when the saw blade is tensioned and secured in position, the extensible legs are held in their adjustment 15 for the reason that these legs cannot lengthen or shorten without lengthening or shortening the saw blade which, of course, may not be done.

19 In the form of the invention shown in Figures 6 to 8, inclusive, the frame comprises a body portion or bridge bar 20 consisting of a solid bar of metal having at one end an angular extension 21 constituting the fixed member of a fixed leg designated generally at 22. A movable tubular member 23 is slidably fitted on the fixed member 21 and carries at its outer end a saw holder 22^a of conventional construction. The tubular member 23 is provided with a lengthwise slot on the opposite sides of which are apertured ears 24 with which a clamping screw or bolt and nut 25 is cooperable to hold the movable member 23 in adjusted position on the fixed member 21, this construction being similar to that employed on the movable leg 8 in Figures 1 to 5 inclusive. A movable leg 26 is provided and is exactly the same as that shown in Figures 1 to 5, inclusive, except as to the holder which is designated at 27 and which is of conventional construction. In other respects the description above of the movable leg 8 is applicable thereto. The portion of the body portion 20 with which the pivoted member 9 is cooperable is toothed or serrated, as at 28.

45 I claim:

1. A hack saw frame including a body portion and a pair of diverging legs carried

50 by the body portion, each leg of the pair comprising a pair of leg members constrained to axial adjustment relative to each other whereby the legs are extensible, one pair of the legs being adjustable along the body portion, the legs having means for holding and tensioning the saw blade, one 55 of the leg members of one of the legs being engageable with the body portion under the influence of said means when the same is tightened up to secure a saw blade in position.

60 2. In a hack saw frame, an elongated bar comprising a body portion and having one end extended at an angle to said body portion to provide a member of a leg, a tubular member adjustably fitted on the extended portion of said bar and providing the other member of the leg, the said tubular member being closed on three sides and having an open side, said tubular member having a pair of ears extending beyond the open side, and a clamping element connecting said ears, a 65 slide adjustable along the portion of the bar which provides the body portion, a bar pivoted to the slide and engageable with the body portion, a tubular member slidably 70 fitted on said pivoted bar, the tubular member being closed on three sides and open on one side, said tubular member having a pair of ears extended beyond said open side, a clamping element connected with said ears 75 and said tubular members being provided with saw holding and tensioning means, the pivoted bar being urged into binding engagement with the body portion when the said means is adjusted to secure and tension 80 a saw blade, the tubular members and the bars on which they are slidably fitted diverging slightly from each other so that the tubular members also diverge slightly 85 from each other whereby when the said means is adjusted to tighten and tension the saw blade the tubular members will be secured in position on the bars on which they are carried.

FRANCIS ALEXANDER STIERHEIM.
